UNITED STATES PATENT OFFICE

150,156

DESIGN FOR A COMBINATION TOOL

Milton C. Neil, Los Angeles, Calif.

Application March 26, 1946, Serial No. 127,962

Term of patent 3½ years

(CL. D54—13)

To all whom it may concern:

Be it known that I, Milton C. Neil, a citizen of the United States, residing in the city of Los Angeles, county of Los Angeles, and State of California, have invented a new, original, and ornamental Design for a Combination Tool, of which the following is a specification, reference being had to the accompanying drawing, forming a part thereof.

The drawing is a perspective view of a combination tool showing my new design.

I claim:

The ornamental design for a combination tool, as shown.

MILTON C. NEIL.
